UNITED STATES PATENT OFFICE.

PETER M. WOLF, OF PLYMOUTH, WISCONSIN.

ROLLER-GATE HINGE.

SPECIFICATION forming part of Letters Patent No. 350,334, dated October 5, 1886.

Application filed May 28, 1886. Serial No. 203,534. (No model.)

To all whom it may concern:

Be it known that I, PETER M. WOLF, a citizen of the United States, residing at Plymouth, in the county of Sheboygan and State of Wisconsin, have invented certain new and useful Improvements in Rollers for Swinging Gates; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 The present invention relates to gate-hinges of the class provided with rollers on which the gate can roll; and the object of my invention is to provide an improved gate-hinge which will not allow the gate to jump the track, so to speak, and which also will work easily without friction.

25 The invention consists in the improved construction and combination of parts hereinafter fully described and claimed, the same comprising a large slightly-flanged roller journaled in the top of an H-shaped casting and a small roller with wide flanges journaled in the bottom of the same casting, which casting also has two lugs on one side for attachment to a 30 hinge-plate by a pivot-bolt.

In the accompanying drawings, Figure 1 represents a side elevation of a gate and roller hinge constructed according to my invention. Fig. 2 is a detail sectional view, and Fig. 3 is 35 a side view, of the roller-hinge.

The frame A of the roller-hinge is made of a single casting in the form of an H, with two lugs, a, projecting from one side opposite the cross-bar a' of the frame.

4 B is the top roller, journaled between the upper arms of the H-shaped frame, and made concave on both sides to give free play between its bearings. The flanges on the roller B are very narrow, so as to cause as little friction as possible, for it has to carry the whole weight of the gate, and they are made just deep enough to retain the bar M of the gate on the roller, acting in concert with the lower roller, C.

45 50 The guide-roller C is journaled between the bottom arms of the H-shaped frame, and it

has wide flanges which embrace the bar N of the gate and prevent the gate from jumping off the roller B. When the gate is moved laterally on the roller-hinge, the friction of the 55 gate-bar N on the flanges of the roller C tends to rotate it in the opposite direction from that in which the roller B is turning, and the roller C, being an independent roller, is free to rotate. The gate-bar N can also set up close to the roller C, so as not to allow any vertical play to the gate on the rollers, all of which tends to make the gate work easy and prevents it from getting out of place. The rollers are made in two parts for convenience in 60 casting. The hinge-plate D has holes d at the top and bottom for attaching it to the gate-post, and has a lug, d', which, in connection with the lugs a and a bolt, E, forms a hinge on which the gate can be swung.

I am aware that hinge-rollers for gates have been used prior to my invention, and that the rollers have been made both plain and flanged, and have been journaled in H-shaped castings. I do not, therefore, claim any of these things, 75 broadly.

Having thus described my invention, what I claim as new, and desire to secure by Letters Patent, is—

1. The H-shaped casting hinged on one side 80 to a plate for attachment to a gate-post, and having the large roller B with narrow flanges journaled between its upper arms, and the small roller C with wide flanges journaled between its lower arms, substantially as shown 85 and described, and for the purpose set forth.

2. A gate-hinge consisting of the hinge-plate secured to the gate-post and provided with the projecting lug d', the H-shaped casting provided with lugs a, the hinge-pin connecting 90 the said lugs, the large roller having narrow flanges journaled between the upper arms of the said casting, and the small roller having wide flanges journaled in the lower arms of the said casting, substantially as set forth. 95

In testimony whereof I affix my signature in presence of two witnesses.

PETER M. WOLF.
